UNITED STATES PATENT OFFICE.

WILLIAM L. HEBERLING AND HENRY HEBERLING, OF HAVANA, ILLINOIS.

METAL ROOFING.

SPECIFICATION forming part of Letters Patent No. 463,831, dated November 24, 1891.

Application filed April 17, 1890. Serial No. 348,420. (No model.)

To all whom it may concern:

Be it known that we, WILLIAM L. HEBERLING and HENRY HEBERLING, citizens of the United States, residing at Havana, in the county of Mason, and State of Illinois, have invented certain new and useful Improvements in Metal Roofing; and we do hereby declare the following to be a full, clear, and exact description of the invention, such as will enable others skilled in the art to which it appertains to make and use the same, reference being had to the accompanying drawing, and to letters of reference marked thereon, which forms a part of this specification.

15 Our invention relates to sheet-metal roofing, more particularly to that class of standing-seam roofing in which one flange of each sheet is folded over and interlocked with an opposite flange of an adjoining sheet.

20 Our object is to provide a double-lock seam in which the fastenings will all be under cover and which can be formed more rapidly and more economically than any other of its class.

Our invention will be better understood by 25 reference to the accompanying drawing.

The figure shows a section of our roofing with its seams in different stages of completion.

30 S and S are sheets or strips of metal roofing with their edges flanged. The flange *a* stands higher than the flange *b*, as shown at A'. The height of *a* is about one and seven-eighths inches and that of *b* one and one-half inches. The flange *b* is secured with 35 common cleats *r*, as at A', and the taller flange *a* is placed against it, and while in this position retaining-hooks *c* are formed at convenient intervals on the edge of the flange *a* and folded down over the edge of the flange *b*, em- 40 bracing it, as there shown. The flanges *a* and

b, with cleats *r*, are now folded over at the dotted line *x x* A' and brought down firmly against themselves, as at A'', thus completing a simple, neat, and efficient double-lock seam.

45 It would not be a departure from our invention to trim off the edge of the flange *a* between the retaining-hooks *c*, as indicated by the dotted line Y Y at A''; nor is it material to our invention whether the sheets receive 50 our peculiar construction wholly on the building or partially at the factory.

A special advantage of the herein-described construction of double-lock seam is its utility in an almost finished condition as a factory 55 product.

What we claim as new, and desire to secure by Letters Patent, is—

1. In combination, the flanges *a* and *b*, the taller flange *a* having retaining-hooks *c* at intervals along its edge, which fold over and embrace the edge of the flange *b*, both flanges thus engaged being folded down against themselves, as shown and described.

2. In combination, the flanges *a* and *b* and 65 cleats *r*, the flange *b* secured to the roof-boards by the cleats *r*, as shown, and the taller flange *a* having retaining-hooks *c* at intervals along its edge, which fold over and embrace the edge of the flange *b*, all the parts 70 thus engaged being folded down against themselves, as shown and described.

In testimony whereof we affix our signatures in presence of two witnesses.

WILLIAM L. HEBERLING.
HENRY HEBERLING.
